(57) CLAIM

The ornamental design for a shrimp cocktail serving container, as shown and described.

DESCRIPTION

FIG. 1 is a perspective view of the shrimp cocktail serving container partially broken away for the ease of illustration;

FIG. 2 is a side elevation view of the invention thereof;

FIG. 3 is a top view thereof;

FIG. 4 is a bottom end view thereof; and,

FIG. 5 is a side cross-section view thereof.

The broken line showing of the shrimp and ice in FIG. 1 is for illustrative purposes only and forms no part of the claimed design.
